UNITED STATES PATENT OFFICE.

HARRISON B. BOZARD, OF HAMILTON, ONTARIO, CANADA, ASSIGNOR, BY MESNE ASSIGNMENTS, TO INTERNATIONAL HARVESTER COMPANY, OF CHICAGO, ILLINOIS, A CORPORATION OF NEW JERSEY.

HOPPER CONSTRUCTION FOR GRAIN DRILLS.

1,404,510.

Specification of Letters Patent. Patented Jan. 24, 1922.

Application filed June 26, 1919. Serial No. 306,960.

To all whom it may concern:

Be it known that I, HARRISON B. BOZARD, a citizen of the United States, residing at Hamilton, in the county of Wentworth and Province of Ontario, Dominion of Canada, have invented certain new and useful Improvements in Hopper Constructions for Grain Drills, of which the following is a full, clear, and exact specification.

10 This invention relates to grain drills and like machines, and more particularly to the hopper construction of machines of this character.

When grain drills are manufactured for 15 foreign shipment it is very essential that they be so designed as to occupy a minimum amount of space in shipment. It is also desirable that the manufacture of different types of hoppers and drills be made as 20 nearly uniform as possible so that many of the same parts may be used in the different types. It is also desirable that the hoppers be so designed that they may be shipped "knock down" and that the means for securing 25 the various parts together when they are assembled, be of such a nature that the parts may be easily and quickly assembled and will be held rigidly together and will not become loosened through use.

Having these ends in view, the present invention has for its object to provide a grain 30 drill construction which will be rigid and may be easily assembled and taken apart, and a construction of hopper which will be 35 tight, preventing loss of seeds.

A further object is to provide a construction which will occupy a minimum amount of space when the parts are shipped "knock down."

40 The construction by means of which these objects are attained comprises, briefly, a hopper having side members and a bottom plate, the bottom plate being securely bolted to the side members and being adapted to fit either 45 wood or steel side members, feeding mechanism secured to said bottom plate, the securing means being shielded from contact with the seeds by means of suitable lining plates.

Referring to the drawings, Figure 1 shows 50 a sectional view of my improved hopper construction;

Fig. 2 is a bottom plan view of the construction shown in Fig. 1;

Fig. 3 is a sectional view similar to Fig. 1,

showing the steel side members and the bottom plates secured thereto;

Fig. 4 is a plan view of a portion of one of the lining plates; and

Fig. 5 is a plan view of a brace member used in connection with the side members.

Referring to Fig. 1, it will be seen that the side members 10 (in this instance formed of wood), are secured to the steel bottom plate 11 by means of bolts 12. It is very desirable that bolts be used as the securing means rather than wood screws, since the wood screws are apt to become loose, thereby preventing the rigid connection between the various parts of the hopper.

The steel bottom plate 11 is flat and has its opposite edges turned up to form inclined attaching flanges and is provided with a feed opening 12' and with elongated slots 13, the seed distributing cups or feeding mechanism 14 being secured to the plate 11 by means of bolts 15 which pass through the slots 13 in the plate 11 and secure the feeding mechanism in the desired position of adjustment. The usual fluted feed wheel 16 is illustrated, but any other desired feeding mechanism may be employed. Usually, the bottom plate carries a series of feeding mechanisms spaced throughout the length of the plate, as indicated by Fig. 2.

From the showing in Fig. 1 it will be seen that the heads of the bolts 15 are disposed below the lower edge of the side members 10, and in order to prevent the seed from coming in contact with the heads of the bolts or from passing into recesses formed between the plate 11 and the lower edges of the side members 10, I have provided elongated lining plates 17. These plates are secured to the side members 10 by means of the bolts 12 above mentioned, and in order to increase the rigidity of the structure I have also provided a series of steel straps 18 which are secured to the side members 10 by bolts 19 and also by the bolts 12 above mentioned. The lining plates 17 extend downwardly into contact with the upper surface of the plate 11, and thereby effectively prevent any of the seed from passing into the recesses in which the heads of the bolts 15 are located. Slots 17' are provided in the plates 17 to permit of the adjustment of these plates so that the plates may be moved into engagement with the upper surface of the plate 11.

In Figure 3 the construction is similar to that shown in Fig. 1, but the side members 10 in this instance are formed of sheet steel and are secured to the bottom plate 11, which 5 is exactly similar to that shown in Fig. 1, by means of bolts 20. The bolts for securing the bottom plate 11 to the feeding mechanism pass through the slots 21 and are protected from engagement with the seed by 10 means of lining plates 22 similar to those shown in Fig. 1, except that the plates 22 are bent at an angle as clearly illustrated in Fig. 3.

It is believed that the assembling and dis- 15 assembling of the parts of the hopper and grain drill will be sufficiently clear from the description above given, and that a further description of the method of assembling is unnecessary.

20 From the above specification it will be readily seen that a simple and efficient construction has been provided, and a construction in which the various parts may be easily and quickly assembled and taken apart. 25 Attention is also called to the fact that the securing means for rigidly connecting the feeding mechanism to the base plate of the hopper is shielded from the contents of the hopper, thereby preventing loss of seed and 30 also assuring the feeding of all the seed in the hopper.

As above pointed out, the use of bolts for securing the various parts together is particularly desirable, both on account of the 35 ease with which the parts may be assembled and taken apart, and on account of the rigidity of the construction when assembled.

While I have in the above specification de- 40 scribed certain specific embodiments of the invention, it should be understood that I do not intend to limit myself to the particular constructions illustrated, but that modifications and changes may be made without departing from the spirit and scope of the 45 invention as expressed by the following claims:

1. A grain drill hopper including a flat bottom plate having upwardly turned edges,

side pieces removably secured to the inner 50 sides of said edges, and lining plates secured to the lower portions of the side members with their lower edges in contact with the bottom plate.

2. A grain drill hopper including a flat 55 bottom plate having upwardly inclined attaching flanges, side pieces on the inner sides of said flanges, lining plates on the side pieces with their lower edges in contact with the bottom plate, and single fastening elements 60 uniting the flanges, side pieces and lining plates.

3. A grain drill hopper including a flat bottom plate, upwardly inclined attaching 65 flanges on the edges of the bottom plate, side pieces secured to the attaching flanges with their lower edges spaced from the bottom plate, and lining plates secured to the side pieces and extending downwardly into contact with the bottom plate. 70

4. A grain drill hopper including a flat bottom plate, upwardly inclined attaching flanges on the edges of the bottom plate, side pieces secured to the inner sides of said flanges with their lower edges spaced from the bottom plate, lining plates secured to the side pieces and extending downwardly into contact with the bottom plate, and a feeding device secured beneath the bottom plate by fastening elements which penetrate the 80 bottom plate back of the lining plates. 75

5. A grain drill hopper including a flat bottom plate with its edges bent upwardly to form attaching flanges, side pieces on the inner sides of said flanges with their lower 85 edges spaced from the bottom plate, lining plates on the side pieces with their lower edges in contact with the bottom plate, single fastening elements uniting the flanges, side pieces and lining plates, and a feeding 90 device secured beneath the bottom plate by fastening elements which penetrate the bottom plate back of the lining plate.

In testimony whereof I affix my signature.

HARRISON B. BOZARD.
